UNITED STATES PATENT OFFICE.

CHARLY W. HUF SCHMIDT, OF PRAIRIE DU CHIEN, WISCONSIN.

DESIGN FOR A COVER FOR MEMORANDUM-BOOKS.

SPECIFICATION forming part of Design No. 28,520, dated May 3, 1898.

Application filed February 24, 1898. Serial No. 871,537. Term of patent 7 years.

To all whom it may concern:

Be it known that I, CHARLY W. HUF SCHMIDT, a citizen of the United States, residing at Prairie du Chien, in the county of 5 Crawford and State of Wisconsin, have invented and produced a new and original Design for a Memorandum-Book Cover; and I do hereby declare the following to be a full, clear, and exact description of the same, reference 10 being had to the accompanying drawings, forming a part thereof.

My invention relates to a design for a memorandum-book cover, and is illustrated in the accompanying drawings, in which—

15 Figure 1 is a perspective view of the cover. Fig. 2 is a central vertical sectional view of the back leaf of the cover. Fig. 3 is a cross-sectional view of the complete cover.

The leading or material features of the 20 design appear in the following description.

A represents the front leaf of the cover, and B the back leaf thereof. This back leaf is provided on its outer side with a facing c, having an ornamental line of stitching d around 25 its exterior edges, and with a concavo-con-

vex holder E, forming a pocket F, open at top and closed at bottom, as shown.

The lower end g of the holder extends inward on a gradual curve, and it is formed with a curved edge h. Extending around this edge 30 and continuing upward along the inner side edge i of the holder is a series of perforations and a continuous line of stitches l, arranged transversely of said edges. The holder is provided on its inner side with a facing m 35 and at its upper edge with an ornamental bead or rim n, having a series of transverse stitches o.

Having thus described my invention, what I claim as new, and desire to secure by Letters 40 Patent, is—

The design for a cover for memorandum-books, substantially as herein shown and described.

In testimony whereof I affix my signature 45 in presence of two witnesses.

CHARLY W. HUF SCHMIDT.
